SPECIFICATION forming part of Design No. 18,417, dated July 3, 1888.

Application filed February 28, 1888. Serial No. 265,590. Term of patent 7 years.

UNITED STATES PATENT OFFICE.

CHARLES P. BUTTON, OF MILWAUKEE, WISCONSIN.

DESIGN FOR A GLOVE.

SPECIFICATION forming part of Design No. 18,417, dated July 3, 1888.

Application filed February 28, 1888. Serial No. 265,509. Term of patent 7 years.

To all whom it may concern:

Be it known that I, CHARLES P. BUTTON, a citizen of the United States, residing at Milwaukee, in the county of Milwaukee and State 5 of Wisconsin, have invented and produced a new and original Design for Knit Gloves or Mittens; and I do declare the following to be a full, clear, and exact description of the same, reference being had to the accompanying photo-

to graph, forming a part thereof.

The accompanying photograph illustrates my design applied to a knit glove.

A shows the back of the glove, and *a a a* represent narrow longitudinal rows or stripes 15 forming the configuration of the entire surface of the back, except at the portions *B B' B*, where these longitudinal rows or stripes *a a a* are interrupted and merged into the wider rows, *b b b*, there being a series of such wider 20 rows extending from the point *c* to the point *d* of each of the portions *B B' B*. These portions *B B' B*, each composed of a series of the wider rows, *b b b*, are rounded at their points *c d*, as

shown, forming stripes with rounded ends, and the central portion, *B'*, is a little longer than 25 the portions *B B* on each side thereof, there being one or more of the narrow longitudinal rows or stripes *a a a* between the central portion, *B'*, and the side portions, *B B*.

I claim—

The design for the surface configuration of the back of a knit glove or mitten, consisting of a series of narrow longitudinal rows or stripes, *a a a*, interrupted and merged into wider longitudinal rows or stripes, *b b b*, said 35 wider rows or stripes being in series and forming the portions *B B' B*, separated by one or more of said narrow rows or stripes *a a*, as shown.

In testimony whereof I affix my signature in 40 presence of two witnesses.

CHAS. P. BUTTON
